TABLE MODEL PRESSING MACHINE

Ernest Davis and Albert Kagi, Syracuse, N. Y., assignors to The Prosperity Company, Inc., Syracuse, N. Y., a corporation of New York

Application September 23, 1930, Serial No. 483,877

4 Claims. (Cl. 68—9)

This invention relates to pressing machines and particularly to pressing machines of the type adapted to be placed on a table or work bench.

The principal object of the invention is to devise a table model pressing machine in which the base portion and yoke member are constructed of pressed metal. A further object of the invention is to form the pressed metal parts comprising the base portion and yoke member into housings for accommodating therein all of the press actuating mechanism. The advantage of constructing a pressing machine of sheet metal is to obtain great strength and rigidity at a substantial saving in weight and expense. The advantage of forming the sheet metal parts so as to form a housing for the press actuating mechanism, is to protect the operator, or any persons standing near the press from being injured by exposed operating levers, to protect the operating mechanism from injury and dirt, and to obtain a more compact and efficient press which is particularly neat in appearance.

A further object of the invention is to provide a pressing machine having a movable pressing element containing electrical heating units which are supplied with power through a conduit which connects with the yoke member, on which the movable pressing element is mounted, at substantially the pivotal axis of the yoke member.

Other objects and advantages will appear and will be pointed out as the description proceeds.

The invention consists in the novel features and in the combinations and constructions hereinafter set forth and claimed.

In describing this invention, reference is had to the accompanying drawings, in which like characters designate corresponding parts in all the views.

Figure 1 is a front elevation of a pressing machine embodying the invention.

Figure 2 is a fragmentary view of the lower portion of one of the pressing elements showing the electrical heating units.

Figure 3 is a side elevation of the pressing machine shown in Figure 1.

Figure 4 is a sectional view of the pressing machine shown in Figure 3.

Figure 5 is a section taken along the line 5—5 of Figure 4.

Figure 6 is an enlarged fragmentary view of a portion of the mechanism shown in Figure 5.

Figure 7 is an enlarged fragmentary view of a portion of the mechanism shown in Figure 5.

Figure 8 is a section along the line 8—8 of Figure 5.

Figure 9 is a sectional view along the line 9—9 of Figure 4.

Referring to Figures 1 and 3, the improved pressing machine includes a base portion 10 which is preferably constructed of pressed metal and is provided with legs 11 by which it rests on a suitable support such as a table or work bench 12. A fixed pressing element or buck 15 is rigidly secured to a neck 16 which is mounted on the base portion 10 and secured thereto by suitable means such as bolts 17. A movable pressing element 20 is mounted on a yoke member 21 in the conventional manner and the yoke member 21 is pivotally mounted on the base portion 10 at 15 23. A handle 25 is mounted on the yoke member 21 and provides means by which an operator may move the yoke member 21 and head 20 to bring the head 20 into contact with the buck 15 to close the press.

The head 20 contains electrical heating units 27 which are mounted on suitable insulating material 28 and contact with the back of a face plate 30 of the pressing head 20. Electrical energy is supplied to the heating units 27 through a conductor 32 which passes from the head 20 25 through the yoke member 21 and through the pivotal connection in a manner later to be described.

A bearing member 35 is secured to the base portion 10 by suitable means such as rivets 36 30 and the bearing member 35 is provided with an upstanding arm 38 which extends above the base portion 10. The yoke member 21 is of substantially U-shaped cross section and mounted with its open side facing downwardly. The upstanding arm 38 extends up into the interior, or chamber, of the yoke member 21. A bolt 40 extends through the forward end of the yoke member 21 and a counter-spring 42 is provided with end members 43 and 44 which connect the spring 42 40 with the upstanding arm 38 and bolt 40, respectively. Due to the fact that the upstanding arm 38 extends above the pivotal connection 23, the counter-spring 42 will tend to move the yoke member 21 to open the press. Thus the counter-spring 42 and the means connecting it with the upstanding arm 38 and bolt 40 provide means for operating the yoke member 21 to move the press into open position.

A slot member 45 is rigidly secured to the yoke member 21 by fastening means 47. The base portion 10 is provided with an opening 50, see Figure 5, and the lower end of the yoke member 21 extends through this opening 50 and into the base portion 10. The yoke member 21 is of suffi- 55

cient width to substantially fill the opening 50 and is curved with respect to the axis of rotation of the pivotal connection 23 so that as the press opens the lower end of the yoke member 21 may 5 move further into the base portion 10.

An operating link 52 is mounted within the base portion 10 on a shaft 54 which is supported in bearing brackets 55 mounted on an adjustment plate 57 (Figures 4 and 5). The bearing 10 between the operating link 52 and shaft 54 includes a slot 60 which permits a limited movement of the operating link 52 transverse to the axis of the shaft 54. A shaft 62 is mounted in suitable bearings such as ball bearings 64 which 15 are contained in a forked end of the operating link 52. The shaft 62 extends through and operates in a slot 65 of the slot member 45. When the press is in open position the shaft 62 will be at the upper end of the slot 65, as shown in 20 dashed lines in Figure 3. When the press is closed, the slot member 45 will move about the axis of the pivotal connection 23 until the shaft 62 is at the lower end of the slot 65, as shown in Figure 4. The slot 65 is provided with a recess 25 portion 66, at the lower end thereof, the purpose of which will be explained hereinafter.

One end of the shaft 54 extends through the end of the base portion 10 and an actuator or 30 operating lever 67 is rigidly secured to this extending end portion of the shaft 54 by suitable means such as a pin 68. A follower yoke 70 is mounted on the shaft 54 on both sides of the operating link 52 between the operating link 52 and the bearing brackets 55, (see Figure 5). 35 The follower yoke is rigidly secured to the shaft 54 by suitable means such as pins 72. A shaft 74 is mounted in the forward end of the follower yoke 70 and is supported in suitable bearings such as ball bearings 75 which are held in place 40 by side plates 77. The side plates 77 are screwed to the follower yoke 70 by screws 79. The members 45, 52 constitute motion transmitting means between the actuator or lever arm 67 which are normally out of cooperative position when the 45 press is open and one of which members is shiftable into operable relation by the closing of the press and by the operation of the actuator.

The operating link 52 is formed with a cam track 82 on the forward end thereof. During 50 closing of the press, the shaft 74 will occupy a position near the top of the cam track 82, as shown in Figures 3 and 4. When the press reaches closed position the lever 67 may be operated to rock the shaft 54 and the follower yoke 70 which is rigidly secured thereto. This rocking movement of the follower yoke 70 will move the shaft 74 downwardly on the cam track 82. The initial downward thrust of the shaft 74 against 55 the track 82 will cause the operating link 52 to pivot about the shaft 54 and raise the shaft 62 into the recess portion 66 of the slot 65. Further downward movement of the shaft 74 will cause the operating link 52 to be thrust rearwardly, to the left in Figure 4, but the recess portion 66 of the slot 65 is of such contour that the shaft 62 will remain in the recess portion 66 and cannot slide upwardly in the slot 65. As the shaft 74 is thus moved downwardly to thrust the operating link 52 rearwardly, to the left in Figure 4, the operating link 52 will slide on the shaft 54, by virtue of the slot 60, and the lower end of the slot member 45 will be thrust rearwardly, to the left in Figure 4, to apply final heavy pressure 70 between the pressing head 20 and buck 15.

The contour of the cam track 82 may be made in any desired form so as to obtain the most efficient mechanical advantage in applying final heavy pressure.

In order to have the shaft 74 in proper position for cooperative action with the cam track 82, means are provided for adjusting the position of the bearing brackets 55 in which the shaft 54 is rotatably mounted. This adjusting means includes the adjustment plate 57 on which the bearing brackets 55 are mounted. The adjustment plate 57 is slidably supported on a base 84 and is held against sidewise displacement by guides 85 which are secured to the base 84. The forward end of the adjustment plate 57 is turned up to 10 provide a flange 86 and the forward and aft movement of the adjustment plate 57 is controlled by an adjustment bolt 88 which is threaded into an adjusting knob 90. The adjustment knob 90 is mounted on the outside of the base portion 10 20 of the pressing machine and may be turned one way or the other to move the adjustment plate 57 forwardly or backwardly so that the shaft 74 will be in proper position for cooperative action with the cam track 82 to apply final heavy pressure to the pressing elements after the press has been closed. This initial closing of the press is effected, as previously described, by pulling downwardly on the handle 25 with sufficient force to overcome the counter-spring 42 which normally holds the press open.

The lower end of the cam track 82 may be formed with a recess which will permit a minute movement of the operating link 52 toward the shaft 74 when the shaft enters this recess in the 35 cam track 82. Such a construction will cause the means for applying final heavy pressure to lock in operated position so that the press will remain closed under heavy pressure until the operator pulls the handle 67 upwardly and thus 40 moves the shaft 74 out of the recess in the cam track 82. When the press is thus released from locked position, the counter-spring 42 will move the yoke member 21 to again open the press. In order to retard the momentum and stop the opening of the press without shock, an air check or shock absorber 95 is oscillatably connected at 96 with the base portion 10 and is pivotally connected at 98 with the lower end of the yoke member 21.

The yoke member 21 is reinforced at its pivotal connection with the base portion 10. This reinforcement includes a cylinder such as a hollow shaft 100 which passes through opposite sides of the yoke member 21. The yoke member 21 is 55 bent inwardly to form flanges 102 which are secured to the cylindrical brace or hollow shaft 100 by suitable fastening means 104. The bearing for the yoke member 21 is provided with a pivot shaft 105 which extends through the hollow 60 shaft 100 and is secured thereto by a bolt 107. The pivot shaft 105 extends through upstanding side portions of the base 10 and is rotatable therein. Bearing blocks 108 are attached to the base 10, as by welding, to increase the bearing surface 65 for the pivot shaft 105.

The conduit 32 which connects with the heating units 27 in the head 20, extends through openings in the hollow shaft 100 and pivot shaft 105 and extends along the axis of the pivot shaft 70 105 to a socket, or other suitable electrical connection 110, which may be connected with a suitable source of electric power such as a drop cord 112.

From the above description it will be apparent 75

that we have provided a pressing machine having a yoke which is so formed that it may be constructed of pressed metal so as to obtain a light rigid yoke member of hollow construction having 5 a chamber therein adapted to receive a part of the press operating mechanism. It will be further apparent that we have provided novel means for furnishing electrical power to a movable pressing element and novel means for operating 10 the yoke member to apply final heavy pressure to the pressing elements.

The invention is illustrated in its preferred embodiment but changes and modifications may be made without departing from the spirit of the 15 invention as set forth in the appended claims.

What we claim is:

1. A garment or laundry pressing machine including a frame, a lever pivotally mounted on the frame, cooperative pressing elements one of 20 which is carried by the lever for movement therewith to open and close the press, a link connected to the lever by a lost motion connection for permitting closing of the press relatively to the link, an operating lever mounted in the frame, 25 connections between the operating lever and the link to move it on its pivot and to thrust it endwise, said lost motion connection and the link having cooperating parts operable to lock the two parts together without lost motion, when 30 the press is closed, upon the pivotal movement of the link, whereby the endwise thrust movement of the link transmits motion to the lever to finally close the press.

2. A garment or laundry pressing machine including in combination a frame; a lever pivotally mounted on the frame; a member formed with a slot having an offset recess portion secured to the lever; cooperative pressing elements, one of 35 which is mounted on the lever for movement therewith to open and close the press; a link having its rearward end portion operating in

the slot to provide a lost motion connection so that the press may close without causing substantial endwise movement of the link; a slide- 5 able pivotal connection between the link and the frame; a cam face on the forward end of the link; manually operated lever means pivotally mounted on the frame; a cam follower mounted on the manually operated lever means in position for cooperative action with the cam face so that when the manually operated lever means 10 is operated the follower will rock the link to move the rearward end into the offset recess and then thrust the link rearwardly to move the head carrying lever and apply pressure to the pressing elements.

3. The combination called for by claim 2 with means for adjusting the slideable pivotal connection forwardly or rearwardly.

4. In a garment or laundry pressing machine, a frame, a lever pivotally mounted on the frame, 20 cooperative pressing elements, one of which is mounted on the lever for movement therewith to open and close the press, means for actuating the lever including a motion transmitting member and an actuator therefor, said motion transmitting member being connected to the lever by a lost motion connection permitting closing of the press relative to said member and also permitting said member to remain idle, said member having two movements, one an endwise 25 thrusting movement and the other an angular shifting movement, the latter movement acting to couple said member and the lever together in motion transmitting relation when the press is closed and the former, thrusting, movement to 30 actuate the lever when so coupled and means operated by the actuator for effecting said two movements.

ERNEST DAVIS.

ALBERT KAGI.
